[57] CLAIM

The ornamental design for a drink through disposable lid for a liquid container, as shown and described.

DESCRIPTION

FIG. 1 is a top plan view of a drink through disposable lid for a liquid container showing my new design;

FIG. 2 is a bottom plan view thereof;

FIG. 3 is a front elevational view;

FIG. 4 is a rear view;

FIG. 5 is an elevational view of the right side thereof; the left side being a mirror image of the right side; and,

FIG. 6 is a perspective view thereof.
